SHIRT CONSTRUCTION

Morris L. Kaplan, Hazleton, Pa.

Application September 18, 1950, Serial No. 185,352

5 Claims. (Cl. 2—128)

This invention relates to shirts, and, particularly, to shirts in which the usual buttons employed for closing the shirt front opening are eliminated in favor of a zipper fastener which is neatly concealed beneath the front facing.

The primary object of the invention is to provide a shirt front facing construction utilizing a zipper fastener, and wherein the front facing, upon being ironed or pressed, will present a neat, plane appearance and not be marred by embossment of the zipper elements through the facing structure to appear upon the exposed area thereof.

Referring to the drawings:

Figure 1 is a sectional view showing one step in making up the shirt front facing;

Figure 2 is a sectional view showing a subsequent step;

Figure 3 is a sectional view showing the final step of making the shirt front facing;

Figure 4 is a sectional view similar to Figure 1 but illustrating a modification wherein a relatively thin cord is employed;

Figure 5 is a sectional view similar to Figure 2 showing a subsequent step in connection with the structure shown in Figure 4;

Figure 6 is a sectional view showing the final step in connection with producing the shirt front facing with the structure shown in Figures 4 and 5;

Figure 7 is a perspective view partly in section showing the construction shown in Figure 1 in use upon a shirt utilizing a zipper fastener for the front opening;

Figure 8 is a perspective view partly in section in which the modification shown in Figure 4 is utilized;

Figure 9 is a sectional view similar to Figure 3 but in which the thermoplastic layer associated with the front facing is omitted in favor of a layer of cloth; and

Figure 10 is a sectional view similar to Figure 8 utilizing the construction of Figure 9.

Referring to the drawings, the cloth of the front shirt section is indicated at 11 and upon the outer surface of the area thereof adjacent the edge of the front opening of the cloth layer 11 is laid two plies of cloth such as "Oxford Weave" indicated respectively at 10 and 10a. The layers 10 and 10a may be separate or be provided by a single piece of cloth folded over to form the layers 10—10a. The layers 11, 10a and 10 are stitched together, as shown at 12, and it will be noted that the intermediate layer 10a which is adjacent the cloth layer 11 of the shirt extends beyond the layer 10, i. e., to the edge of the shirt layer 11, as shown in Figures 1 and 2.

A zipper stringer 13 is stitched at 14 to the layers 10a and 11, either before or after the stitching 12. The stringer of the zipper before being stitched at 14 is folded upon itself, as shown, and the folded-over portions are stitched together, as shown at 13'.

Thereafter, the layer of cloth 10 is folded upon itself, as shown at 15 in Figure 2, to provide a multi-ply structure, and a shirt front facing 16 having a cloth layer enclosing a thermoplastic layer T is stitched to the layers 10a and 11, as shown at 17, either before or after said layer 10 is folded.

Referring to Figure 3, the shirt front facing 16 is then folded over and its free edge is stitched to the shirt layer 11, as shown at 18. By this construction it will be observed that the zipper element on the stringer 13 is nested in a recess R where it rests upon the plies 10a and 11 beneath the facing 16 while, to the right of the zipper element, a thickness is developed by reason of the ply 11, the ply 10a, the multiple plies 10, and the folded-in ex-

2

tended portions of the plies 10a and 11 disposed between the multi-ply 10 and the under surface of the shirt front facing 16.

Referring to Figures 4, 5 and 6, the steps of making the shirt and the structure utilized are identical with that shown in Figures 1, 2 and 3, except that a thin cord 19 is positioned on the upper face of the fabric layer 10 and stitched to the layers 11, 10a and 10, as shown by the stitching 12. The presence of the cord 19, as shown in Figure 6, increases the thickness of the front facing to the right of the zipper element.

Referring to Figure 9, instead of using a thermoplastic layer T, this may be omitted in favor of a layer of suitable cloth, indicated as a whole at 20.

Referring to Figure 7, it will be observed that the mating zipper elements will be so disposed that when the garment is pressed or ironed, there will be complete avoidance of embossment of the zipper elements upon the front of the shirt facing 16. In Figure 7 I have shown the opposite and underlying edge or facing of the shirt opening at 22 to which is stitched at 23 the mating zipper element 25 and with the zipper elements engaged in the usual manner, as shown at 26.

The recess R which is illustrated in Figures 3, 6 and 7 to 10, whereby the zipper element on the overlying facing layer 16 is nested adjacent a relatively thick layer of cloth plies, assures that whether the shirt front facing 16 employing a thermoplastic layer T or simply a cloth layer 20 be employed, there will be a sufficient protective thickness to prevent the zipper elements embossing through to the exposed surface of the shirt front facing 16. Hence, the front facing has its exposed surface plane and neat appearing at all times and effectively conceals the presence of the zipper elements.

It will be observed from the foregoing that I have provided a method of making a shirt comprising attaching to a layer of cloth 11, forming the front section of the shirt, adjacent the front edge opening thereof as shown in Figure 1, a plurality of superposed fabric plies 10 and 10a in overlying relation to the shirt layer. One of said fabric plies 10a, adjacent the shirt layer 11, is of greater area, and another remote or exposed fabric ply 10 superposed thereon is of lesser area. The stringer 13 carrying the zipper element is attached to the shirt layer 11 and the adjacent fabric ply 10a of greater area at one side of the fabric ply 10 of lesser area as shown in Figure 2. At the other or opposite side of the fabric ply 10, the shirt front facing 16 is attached at one of its edges to the shirt section and to the fabric ply 10a of larger area at a point remote from the zipper element as shown at 17 in Figure 2 and is then folded over so that its other edge is disposed over the shirt section 11 and stitched thereto at 18 to thus conceal and enclose the fabric plies 10—10a between the shirt layer 11 and the facing 16. The method further involves forming the recess R by providing an increased thickness of material to one side of the zipper element as shown and extending toward the front opening edge of the shirt which edge may be said to consist of either the free outwardly extending edge of the facing 16 as shown in Figure 3 or the folded-over and turned-in adjacent portions of the ply 10a and shirt layer 11 which are stitched to the facing at 17 or both, also as shown in Figure 3. Instead of folding over the fabric ply 10, or folding it to provide a double thickness, two or more separate plies may be employed, there being at least three of the fabric plies 10—10a between the shirt layer 11 and the facing 16.

The important feature is the provision of the recess R due to the increased thickness created at one side of the zipper element extending toward the front opening edge of the shirt. This increased thickness is provided by the superposed fabric layers 10 and 10a and the folded-over and in-turned edge portions of the shirt layer 11 and fabric ply 10a as shown in Figure 3 remote from the zipper element, i. e., at the front opening edge of the shirt. Where a cord is employed to increase the thickness, it is enclosed in the folded edge portion of fabric ply 10 as shown in Figure 4.

I claim:

1. A shirt front formed of a layer of fabric, plies of fabric attached to the shirt layer in superposed relation

adjacent the front opening edge of the shirt front, a front facing attached to the shirt layer and concealing the same and said fabric plies at the front opening edge of the shirt front, a stringer carrying a zipper element attached to the under side of the shirt layer and one of said fabric plies remote from the front opening edge of the shirt front, said shirt layer and superposed fabric plies adjacent one side of the element providing an increased thickness of material extending toward the front opening edge of the shirt front and defining a recess in which said element is nested.

2. A shirt front according to claim 1 in which said increased thickness has at least three of said fabric plies in superposed relation between the shirt layer and said facing.

3. A shirt front formed of a layer of fabric plies of fabric attached to the shirt layer in superposed relation adjacent the front edge opening of the shirt front, a front facing attached to the shirt layer and concealing the same and said fabric plies at the front opening edge of the shirt front, a stringer carrying a zipper element attached to the under side of the shirt layer and one of said fabric plies remote from the front opening edge of the shirt front, another of said fabric plies being folded upon itself to extend from adjacent one side of the element toward the front opening edge of the shirt front, said shirt layer

and superposed fabric plies adjacent one side of the element providing an increased thickness of material extending toward the front edge opening of the shirt front and defining a recess in which said element is nested.

5. A shirt front according to claim 3 in which a cord is enclosed in the folded edge portion of said other folded fabric ply.

6. A shirt front according to claim 1 in which edge portions of the shirt layer and a fabric ply adjacent the front opening edge, are folded inwardly in superposed relation to said shirt layer and superposed fabric plies at the said one side of the element and in concealed relation to said facing.
